UNITED STATES PATENT OFFICE.

ABRAHAM BLUM, OF SAN FRANCISCO, CALIFORNIA.

COPY-HOLDER FOR TYPE-WRITERS.

1,251,329.

Specification of Letters Patent. Patented Dec. 25, 1917.

Application filed August 14, 1914. Serial No. 856,829.

To all whom it may concern:

Be it known that I, ABRAHAM BLUM, citizen of the United States of America, residing at No. 21 Flood avenue, San Francisco, in the county of San Francisco and State of California, have invented certain new and useful Improvements in Copy-Holders for Type-Writers; and I do hereby declare the following to be a full, clear, and exact description of the invention, such as will enable others skilled in the art to which it appertains to make and use the same.

This invention relates to a copy holder and line indicator especially designed for attachment to typewriters.

The invention has for its object to provide a copy holder of simple and efficient construction embodying means whereby the same may be quickly and reliably secured in operative position upon the frame of a typewriter.

Another object is the provision of an arm constituting an indicator and having connection with suitable operating means whereby the typist may move the indicator arm downwardly as the work supported by the holder is transcribed.

Another object is the provision of manually operable means for releasing and automatically moving the indicator arm to its initial position.

With these and other objects in view, the invention consists in the novel construction, arrangement and formation of parts as will be hereinafter specifically described, claimed and illustrated in the accompanying drawings, in which:

Figure 1 represents a side elevation of the copy holder attached to a typewriter, the latter being shown in dotted lines.

Fig. 2 represents a perspective view of the copy holder removed.

Fig. 3 represents a front elevation of the copy holder partly broken away.

Fig. 4 represents an enlarged side elevation thereof, partly broken away.

Fig. 5 represents an elevation on the opposite side of the holder, partly broken away.

Fig. 6 represents a top plan view, partly broken away.

Fig. 7 represents an enlarged side elevation of the holder, partly broken away, detached.

Fig. 8 represents an enlarged front elevation, partly in section, of the frame structure of the holder.

Fig. 9 represents a top plan view, partly broken away, of the lower portion of the frame structure of the holder, showing in detail the adjustable securing means.

Fig. 10 represents a side elevation of the latch bar and pawl releasing member removed.

Fig. 11 represents a rear elevation of the rack bar and pawl releasing member removed.

Fig. 12 represents an enlarged detail view, partly broken away, of the spring operating the indicator.

Fig. 13 represents a diametrical sectional view through the spring and casing therefor.

Fig. 14 represents a top plan view of the spring mechanism.

Fig. 15 represents a top plan view of the pulley.

Fig. 16 represents a side elevation of the pulley, and

Fig. 17 represents a rear elevation of the guide member for the rack bar.

Fig. 18 represents a top plan view of the guide member.

Referring to the drawing in detail, where-

in similar reference numerals designate cor-

responding parts throughout the several

views, the numerals 20 and 21 indicate a pair

of L shaped bars, having the adjacent ends

overlapped. One of the overlapped ends of

the members 20 and 21 is provided with a

threaded opening receiving the wing bolt

22, slidably mounted within a slot formed

longitudinally in the other member, whereby

the L shaped bars 20 and 21 may be

ator. The plate 29 is provided centrally with a depending portion 31 to which is pivotally secured the spring actuated gripper 32 operating against the top face of the plate 29 and in a cutaway portion formed in the flange 30 for holding the copy or sheet in position on the supporting plate 29.

A guide 33 is secured to the rear face of the plate 29 adjacent one of its vertical edges and is provided in its rear face with a channel 34 formed with inwardly diverging walls receiving the similarly shaped projection 35 formed longitudinally of the rack bar 36 formed with laterally and outwardly projecting teeth 37. A spring 37^a is secured to the rear face of the rack bar 36 and carries an arm 38 constituting a line indicator. The tension of the spring 37^a normally retains the arm 38 in sliding contact with the front face of the plate 29, but is sufficiently flexible to permit the insertion of a relatively thick object between the arm and the plate.

A shaft 40 is hingedly secured to the plate 29 in spaced relation to the rack bar 36, and one end of a spiral spring 41 is permanently secured thereto. The opposite extremity of the spiral spring 41 is secured interiorly of a cylindrical casing 42 rotatably mounted on the shaft 40 and provided with a circumferential channel 43 receiving the flexible strip 44 secured at one end to a post 45 secured transversely in the casing 42 and secured at its opposite extremity to an eyebolt 46 carried by the upper extremity of the rack bar 36. A pulley 42^a is rotatably mounted above the rack bar 36, and provided with a circumferential channel 43^a to act as a guide for the flexible strip 44. The tension of the spring 41 normally retains the rack bar 36 in elevated position, and said rack bar is normally locked against the action of the spring by a pawl 47 secured to the rear face of the plate 29.

45 A shaft 48 is mounted for vertical sliding movement on the rear face of the plate 29 in suitable bearings 49, and is normally retained in elevated position by the tension of a spring 50 coiled about the medial portion of the shaft 48 and secured at one end to said shaft and at the opposite end to the bearing 49. The shaft 48 carries adjacent its lower extremity a sleeve 51 to which is pivotally secured a pawl 52 normally retained in engagement with the teeth 37 of the rack bar 36 by the tension of a spring 53. An abutment 48^a is secured to the rear face of the plates 29 for limiting the upward movement of the shaft 48.

60 An arm 55 is pivotally supported at one end in the rear portion of the frame structure 27 and is connected with the operating lever 56 by a link 57. The operating lever 56 extends forwardly to a point adjacent to the keys of the typewriter, and is provided

with a suitable operating key 58. The forward extremity of pivoted arm 55 is pivotally secured with the lower reduced extremity of the vertically movable shaft 48, whereby when the operating lever 56 is depressed the shaft 48 is moved downwardly through the link 57 and the interposed arm 55.

A pawl releasing bar 59 is pivotally secured at 60 to the lower extremity of the rear face of the rack bar 36 and extends upwardly on said rack bar. A handle 61 is rigidly secured to the bar 36 and adjacent the upper end thereof, and a hand lever 62 is pivotally secured at 63 on the rear face of said rack bar below the handle 61. The inner extremity of the hand lever 62 is provided with a cam 64 engaging the releasing bar 59, which latter is normally retained inwardly of the points of the teeth 37 by the tension of a spring 65 secured at its upper end to the hand lever 62 outwardly of the pivotal axis of the latter and at its lower end to the medial portion of the releasing bar 59. When the hand lever 62 is lifted the bar 59 is swung outwardly toward the points of the teeth 37 engaging the pawls 47 and 52, thus releasing the latch bar 36 and permitting the latter to move to its initial or elevated position, carrying therewith the indicator arm 38.

In use, the holder is attached to the typewriter 26, as illustrated in Fig. 1, and the book or sheet containing the matter to be read or copied is positioned on the plate 29 and supported by the forwardly directed flange 30 and spring actuated gripper 32. As the matter on the several lines of the book or sheet are copied the line indicator 38 is moved downwardly by depressing the lever 56, the movement of the lever 56 being transmitted through the link 57, arm 55, shaft 48, pawl 52, rack bar 36 to the indicator 38. When the operating lever 56 is released it is automatically returned to its normal position by the tension of the spring 50. The movement of the operating lever 56 and the coöperating parts is limited by a set screw 68 secured to the forward extremity of the L shaped bar 20. When it is desired to move the indicator 48 to its initial position, the handles 61 and 62 are gripped by the operator, lifting the lever 62 and swinging the release bar 59 outwardly by the action of the cam 64. The outward movement of the releasing bar 59 disengages the pawls 47 and 52 from the teeth 37 of the rack bar 36 and permits the rack bar and indicator 38 to move upwardly under the influence of the spring 41.

What I claim is:

1. A copy holder comprising a frame, a plate secured to the frame, a rack bar slidably carried by the plate, spring means normally retaining the rack bar in elevated position, a shaft slidably mounted on the plate,

spring means normally retaining the shaft in elevated position, means to depress the shaft, a spring pressed pawl pivoted to the shaft and engaging the rack, a second pawl pivoted to the plate and engaging the rack bar, a releasing arm pivoted to said rack bar for engaging both pawls, and means carried by and movable with the rack bar to force said arm into engagement with the pawls to release the rack bar and permit the latter to move outwardly under the influence of the first-mentioned spring means.

2. A copy holder comprising a frame, a plate secured to the frame, a rack bar slidably carried by the plate, spring means normally retaining the rack bar in elevated position, a shaft slidably mounted on said plate, spring means normally retaining the shaft in elevated position, means to depress said shaft, a spring pressed pawl pivoted to the shaft and engaging the rack bar, a second pawl pivoted to the plate and engaging the rack bar, a releasing arm pivoted to the rack bar for engaging both pawls, a hand lever pivotally secured to the rack bar and movable therewith, and a cam carried by the

hand lever for engaging the pawls and releasing the rack bar.

3. A copy holder comprising a frame, a plate secured thereto, a rack bar slidably carried by said plate, spring means to normally hold said rack bar in elevated position, a shaft slidably supported on said plate, spring means normally tending to elevate said shaft, means to depress said shaft, a spring pressed pawl pivoted to the shaft and engaging the rack, a second pawl pivoted to the plate and engaging the rack bar, a releasing arm pivoted to the rack bar for engaging both pawls, a handle rigidly secured to the rack bar and movable therewith, a lever pivotally secured to the rack bar below the handle, a cam carried by the lever for engaging and swinging the releasing arm to disengage the pawls from the rack bar, and means normally retaining the hand lever in inoperative position.

In testimony whereof I affix my signature in presence of two witnesses.
